FLASHLIGHT

Orville T. Wood, Clinton, Mass., assignor to
 Blake Manufacturing Corporation, Clinton,
 Mass., a corporation of Massachusetts

Application July 11, 1940, Serial No. 344,879

5 Claims. (Cl. 240—10.66)

This invention relates to electric flashlights and hand lanterns of the kind in which a removable battery of dry cells is connected and disconnected at will to an incandescent lamp from which the light is reflected in a given direction.

An electric hand lantern or flashlight has heretofore been proposed in which the light from the lamp may be selectively thrown as a beam or spotlight, that is, concentrated on one spot, or as a diffused light spread over a wider area. This has been accomplished, in some situations, by a sleeve comprised, say, of frosted glass which is movable between a position between or surrounding, as the case may be, a lamp with respect to a reflector whereby the light rays are diffused and a position in which the light rays are not intercepted by the screen whereby the light rays are directed by the reflector as a beam.

It has also been proposed to so mount a lamp within a reflector that the filament of the lamp, which, of course, is the light source, is definitely fixed against displacement at the focus of a reflector.

The present invention has for one of its objects to selectively throw a beam of light, that is, concentrate the light at one spot or alternatively diffuse the light over a wider area. In carrying this aspect of the invention into effect, a reflector is provided composed of a plurality of parts, one at least of which is relatively movable with respect to an adjacent part.

A further object of the invention is to utilize a fixed reflector for one type of light and a relatively movable reflector for a second type of light. In carrying this object of the invention into effect, in its preferred embodiment, a fixed reflector is so disposed with respect to a source of light and is so proportioned as to normally receive the light rays from the light source and direct them as a beam of light while a second reflector is movable into position to spread the light from the light source and give in effect a light diffused over a relatively wide area.

Another object of the invention is the provision of reflector sections one of which is relatively fixed with respect to a fixed light source and the other of which is relatively movable with respect to the first reflector to change the characteristics of the light. In carrying this aspect of the invention into effect one of the reflectors telescopes with respect to the other reflector.

Yet another object of the invention is to selectively concentrate the light from a light source. To this end, a shield-like member of predeter-

mined characteristics is movable relative to the lamp from such position that substantially no light from the lamp strikes a reflector to a position at which all of the light from the lamp is received by the reflector and thrown in a predetermined direction.

It is also an object of the invention to support the movable reflector in a flashlight or hand lantern. In carrying this aspect of the invention into effect, the movable reflector is carried with a slidably actuating device adapted to be selectively actuated at the option of the user.

Still another object of the invention is a flashlight or hand lantern having provision for closing the circuit between the source of light and the source of electrical energy coincident with the pre-selection of the type of light desired.

A further object of the invention is a light transmitting closure for the reflector of varying light transmitting characteristics. Accordingly, the light transmitting closure may have one area of a refractive index different from that of another area. In the illustrated embodiment the central portion of the light transmitting closure is conveniently formed as a plano-convex lens while the peripheral portion of the closure may take a plate-like form.

The invention also seeks a hand lantern or flashlight which is practical from the standpoint of ease and cheapness of manufacture and durability and effectiveness in use.

These and other objects of the invention and the means for their attainment will be more apparent from the following detailed description, taken in connection with the accompanying drawing illustrating one embodiment by which the invention may be realized and in which:

Figure 1 is a view substantially entirely in longitudinal axial section showing a flashlight to which this invention may be applied and illustrating particularly the relation of parts when the circuit is open;

Figure 2 is a fragmentary view similar to Figure 1 but with the reflector in position to diffuse the light from the lamp source over a relatively extended area, that is, a "flood-light";

Figure 3 is a view similar to Figure 2, showing the reflector in position to direct a concentrated beam of light, or "spot-light";

Figure 4 is a transverse sectional view taken in the plane indicated by the line 4—4 of Figure 1, looking in the direction of the arrows; and

Figure 5 is a fragmentary view showing the circuit closer actuating device taken in the plane

indicated by the line 5—5 of Figure 1 and looking in the direction of the arrows.

The flashlight or hand lantern of this invention comprises generally a casing 8 of any desired configuration illustrated as cylindrical and formed with threads 10 at its upper end. The rim is inwardly deflected, as at 12, and then outwardly deflected in a transverse plane, as at 14, to the cylindrical plane of the casing 8 and then upwardly as at 16 in that cylindrical plane to be again bent inwardly as a lip at 18 over a lamp socket supporting disc 20 of non-conductive material supported on the transverse ledge 14.

The disc 20 is preferably formed centrally thereof with an aperture 22 to receive the lamp socket 24, portions of which are crimped over and under the edge of the aperture 22 to retain the lamp socket in position. This lamp socket support receives and supports in proper position the lamp 26.

Secured to the lower surface, as viewed, of the lamp socket supporting disc 20 is a disc-like contact member 28 also apertured to register with the aperture 22 of the lamp socket support and retained in position against the disc 20 by the outwardly turned lower end 30 of the lamp socket 24. The edge of the contact member 28 is bent downwardly and is curvilinear in vertical cross section preferably on the arc of a circle as indicated at 32 to permit a circuit closure contact element indicated generally by the numeral 34 to easily position itself in electrical connection with the contact member 28.

Inwardly of the lamp socket support 24 and in the lower portion thereof is a non-conductive sleeve 36, conveniently extending below the outwardly turned end 30 of the lamp socket support and secured in any convenient fashion as by a forced fit within the lamp socket. Also mounted within the contact shell 28, 32 is a generally rectangular or elongated insulating strip 38 of non-conductive material of a thickness in the axial direction of the casing 8 greater than the thickness of the outwardly turned end 30 of the lamp socket support which is received within an aperture 39 formed in the strip and which serves together with the sleeve 36 to prevent electrical contact with the lower portion of the lamp socket. Disposed within the sleeve 36 and supported by the insulating strip 38 is an upwardly bent leaf spring contact 42 which is secured by means of one of the rivets 40 which secure the insulator 38 to insulating disc 20, the rivets 40 passing through oversize holes in the contact member 28, as will be understood. Contact member 42 is adapted to make yielding contact with the center terminal of the lamp base 44. Contact 42 is in direct electrical connection with a transversely extending contact member 46 which makes contact with the central terminal 48 of the battery 49. Contact 46 is held in place by the two rivets 40. The electrical circuit between battery terminal 48 and lamp terminal 44 includes contact 42, rivet 40 and contact 46.

Slidable along the inner surface of the casing 8 is an actuating member 50 offset inwardly, as at 52, and passing outwardly of contact member 32 through a slot or notch 54 formed in the insulating lamp socket support 20. Above the lamp socket support 20 the actuating member 50 is bent inwardly in a radial direction, as at 56, and is formed with an aperture 57 of a diameter greater than the aperture of the lamp socket 24 with which it is concentric but in spaced relation.

Mounted within the aperture in the actuating member 50 is a frusto-conical reflector member 58 the lower end of which is crimped, as at 60, around the edge of the aperture in the actuating member. The crimped portion 60 is insulated as by an annular insulating collar 62, channel shaped in cross section, to prevent accidental short circuit between the lamp base and the reflector.

10 The reflector 58 is moved by the actuating member 50 inwardly and outwardly of a fixed reflector 64 formed with a rim 66 at its outer end suitably insulated, if desired, as at 68, and mounted on the threaded end 70 of a hood member 72 conveniently threaded on the threaded end 10 of the flashlight casing.

15 In the drawing, the reflector 64 is illustrated as a parabolic reflector fixed with respect to the light source and directs a beam of light therefrom. It is formed in its inner end with an aperture 73. The frusto-conical reflector 58 is movable from a position without the reflector 64 to a position within the reflector 64 to intercept the light from the light source. The reflector may, if desired, direct a diffused light from the light source. To this end, the light reflecting characteristics of the reflecting means of the shield-like member 58 may have an inner reflecting surface or reflecting means of predetermined but different characteristics from the characteristics of the reflecting means 64.

20 Resting on the rim 66 of the reflector or the insulation 68 thereon, as the case may be, is a so-called lens 74, 76 whereof the central portion 76 is illustrated of a shape such as plano-convex so as to have refracting characteristics while the peripheral portion 74 may have plane parallel surfaces to permit light to pass therethrough without refraction. As shown, the edge of the aperture 73 at the inner end of the fixed reflector 64 is outwardly bent to form an edge or stop 80 against which the inwardly bent end 56 of the actuating member may contact or, as illustrated, an eyelet 82. Eyelet 82 retains an angularly shaped piece of insulation 84 on the inner surface of the actuating member which is adapted in the Figure 1 position to insulate the angularly bent upper end 83 of the contact member 34 thereof from the conductive member 32. As illustrated, the contact member 34 is a ribbon or strip of conductive material bent outwardly as at 36 at its lower end and passed through an aperture 37 in the actuator portion and held in position by the downwardly bent extremity 83 thereof.

25 The electrical circuit between the zinc cup terminal of the battery 49 and the lamp base 45 includes casing 8, slide 50, yielding contact 34, contact member 28 and lamp socket 24.

30 The circuit closing member of this invention and the actuating member associated therewith has three positions, to wit, an open circuit position illustrated in Figure 1, a closed circuit position illustrated in Figure 3 and a second closed circuit position illustrated in Figure 2. In the position of Figure 1, which is the open circuit position, the movable reflector 58 is in inoperative position, but the circuit being open, no light is at this time emitted from the lamp 26. When 35 the actuating member 50 is moved to the position illustrated in Figure 3, the circuit is closed by contact of the member 34 with the conductive member 28, but the movable reflector 58 is at such position with respect to the fixed reflector 64 that reflector 58 receives no light rays or sub-

stantially none from the lamp and all the light rays fall upon the reflector 54 and are directed as a beam of light or, as it is called, a "spot-light" through the transparent closure 74, 76. When, however, a diffused light, or as it is called, a "flood-light," is desired, the frusto-conical shield or reflector 58 is moved to the position shown in Figure 2 where the light from the light source 26 falls only on the transparent closure 74, 76 through which it passes as a diffused light or, as it is called, a "flood-light."

To actuate the combined circuit closure and reflector actuator 50, the casing 8 is provided with three axially aligned apertures of generally circular shape the lowermost being indicated at 90, the intermediate one at 91 and the uppermost one at 92, which apertures are joined by axial slots 94 and 95. A plunger 96—99 is adapted to move in these apertures and slots. This plunger 96—99 is shown as having a thumb piece or push button 96 formed with an enlarged inner rim 97, a shank portion 98, and an enlarged inner end portion 99. The collar or rim 97 prevents outward movement of the button in the aperture 102 in the depressed portion 103 of a slide 104 while the plunger 96—99 tends to remain in its outermost or protracted position, being urged by a resilient strip 106 secured at its lower end by an eyelet 107 to the lower end of the actuating member 50. At its upper end 108 the spring 106 bears on or, if desired, may be secured to the enlarged inner portion 99 of the plunger 96—99. Obviously, the opposed side edges of the slide may be conveniently provided with tongues, not shown, passed through parallel slots, also not shown, in the casing 8 and bent inwardly, as is common in the art, to retain the slide 104 on the casing 8 and limit its axial movement.

It will be observed that in the Figure 1 or inoperative position, the insulatory member 84 is interposed between the contact 34 and the conductive member 32 so that the circuit between the lamp casing and the lamp is interrupted. In this position, the locking plunger 96—99 of the slide is in the lowermost aperture 90 as illustrated in Figures 1 and 5. In order that the reflector 58 assume the position of Figure 3, the thumb piece or button 96 is depressed until the shank 98 thereof lies in register with the slot 95 in the casing and is then advanced to the second aperture 91 which the enlarged inner end is permitted to enter to retain the actuating member 50 and reflector 58 in the position of Figure 3 or "spot-light" position. When a "flood-light" is desired to be emitted from the flashlight, the plunger is again depressed and the slide advanced to the uppermost aperture 92 which the enlarged portion 99 is again permitted to enter to lock the slide in its most advanced position. That is the position illustrated in Figure 2.

The operation of the flashlight of this invention should be apparent from the foregoing description. Suffice it to say that a flashlight is provided by this invention which affords either a spotlight or a diffused light and the relative movement with respect to the light source is conveniently, although not necessarily, effected by the same instrumentalities that close the circuit at either operative position of the reflector and open the circuit coincidentally with movement of the reflector to a non-operative position. It will be readily understood, however, that the invention is not limited to coincidental movement of the circuit closure and reflector since a separate circuit closure may be readily provided by

those skilled in the art, and in that event, for instance, the reflector need be capable of movement only between the positions illustrated in Figures 2 and 3.

Various modifications will occur to those skilled in the art in the composition, configuration and disposition of the component elements going to make up the invention as a whole as well as in the selection and combination of particular elements of this invention to accomplish specific purposes and no limitation is intended by the phraseology of the foregoing description or illustrations in the annexed drawing except as indicated in the appended claims.

15. What is claimed is:

1. In a flashlight, in combination, a source of light, a fixed reflecting means normally receiving light, a second reflecting means comprising a shield having an interior reflecting surface, circuit closing means, manually actuated actuating means supporting said second reflecting means and the circuit closing means and moving said second reflecting means between a circuit open position, a circuit closed position and a second circuit closed position at which the second reflecting means is interposed between the light source and the fixed reflecting means and intercepts light from the light source.

2. In a flashlight, in combination, a lamp socket, a support therefor, a first reflector formed with an aperture and stationary with respect to the lamp socket support, an actuating strip slideable longitudinally of the casing, a frusto-conical shield member having an inner reflecting surface carried by the actuating strip to surround the lamp socket and move in the first reflector aperture between two positions of the actuating strip at which a circuit is closed, circuit closing means at the aforesaid two positions, means on the strip to close the circuit at either of said two positions, a slide on the casing operatively connected with the actuating strip and manually actuatable means on the slide to releasably lock the actuating strip in the aforesaid two positions and in a third position at which the circuit is open.

3. In a flashlight, in combination, a lamp socket, a support therefor, a contact carried thereby, a first reflector formed with an aperture and stationary with respect to the lamp socket support, an actuating strip slideable longitudinally of the casing, a second frusto-conical shield member having an inner reflecting surface carried by the actuating strip to surround the lamp socket and move in the first reflector aperture, a contact carried with the actuating strip and adapted to make contact with the contact on the lamp socket support in two positions of the actuating strip, a slide on the casing operatively connected with the actuating strip and manually actuatable means on the slide to releasably lock the actuating strip in said two positions and in an open circuit position.

4. In a flashlight, a relatively fixed parabolic reflector, a light source substantially at the focal point of the reflector, an opaque shield movable coaxially of the light source and having a reflecting surface directing a diffused light therefrom and facing toward the light source, said reflecting shield being movable from a position interposed between the parabolic reflector and the light source to a position permitting the parabolic reflector to receive light from the light source and a plane lens formed centrally with a condensing lens portion comprising a minor portion of the lens area to enhance the flood light

effect of the flashlight when the movable shield is in interposed position.

5. In a flashlight, in combination, an electrical circuit comprising a source of light and a source of electrical energy, reflecting means fixed with respect to the light source to direct the light rays as a beam of light, an opaque shield having an interior reflecting surface of characteristics to reflect a diffused light, a manually actuated

member to move said opaque shield from an inoperative position to an operative position between the light source and the fixed reflector to intercept and reflect the light from the light source as a diffused light, circuit closing means, said manually actuated member causing said circuit closing means to close said circuit when said opaque shield is in an operative position.
